UNITED STATES PATENT OFFICE.

CHARLES E. SEYMOUR, OF HURLEY, WISCONSIN.

CONCENTRATOR.

SPECIFICATION forming part of Letters Patent No. 436,807, dated September 23, 1890.

Application filed December 21, 1889. Serial No. 334,552. (No model.)

To all whom it may concern:

Be it known that I, CHARLES E. SEYMOUR, of Hurley, in the county of Ashland and State of Wisconsin, have invented new and useful 5 Improvements in Ore-Concentrators; and I do hereby declare the following to be a full, clear, and exact description of said invention, reference being had to the accompanying drawings, and to the letters of reference marked 10 thereon, which form a part of this specification.

My invention relates to a device for use in ore concentration in which the ore is separated from the lighter intermingled material 15 by the use of water through the action of centrifugal force and the attraction of gravitation.

In the drawings, Figure 1 is an elevation of my concentrator, the bowl being shown in central vertical section and other parts being 20 broken away to show the interior construction. Fig. 2 is a top plan view of the bowl and encircling trough, parts being broken away to show the interior.

A is the frame on which my device is supported. A vertical rotating shaft B is provided with a fixed pulley C, on which runs the power-supplying cable D. A circular concave bowl E is fixed to the shaft B, which passes water-tight through it centrally. This 25 bowl is adapted to receive a supply of the ore mingled with refuse. A water-supply pipe F leads into the bowl, and preferably has its discharge near the bottom of the bowl, and is adapted to supply water for washing the

30 refuse from the ore. A circular trough G, supported on the frame, is located close about the bowl, having its inner edge within a re-curved flange or lip H, formed on the edge of the bowl. A waste-pipe I leads away from

35 the trough G. A short discharge-pipe K leads from the bowl at its bottom, which discharge-pipe is provided with a gate L, adapted to close the pipe, and a plate-stopper M is preferably located on the interior surface of the 40 bowl over the orifice of the discharge-pipe to keep ore or sediment out of the pipe until it is desired to let it pass into the pipe. An additional removable section of pipe or hose K' may be coupled to the pipe K for leading the

45 pipe away from the bowl to a greater distance, when desired.

A block N, fixed to the lower part of the

frame A about the shaft B, is provided with a diametrical crown-projecting cam or step N', and a collar O, about the shaft B, and affixed thereto, is located above the block N, and is provided with a recess O', adapted to receive therein the step N', so that when the shaft is in the position shown in Fig. 1 the block and collar will be close together; but as the shaft is rotated the collar and shaft will be raised to the extent of the height of the step N' as the recess passes away from the step and will drop down again on the step as the recess comes to it, whereby the 65 bowl as the shaft is rotated is given an intermitting vertical or pumping movement. This vertical movement of the shaft is also preferably controlled to a limited extent by the springs P and P'. The spring P rests on 70 a sleeve R, which turns by a screw-thread into a plate S, bolted to the frame A. At its other end the spring P bears against a collar R', movable on the shaft B and bearing at its upper edge against the lower surface of 75 the bowl E. The spring P' at one end bears against a sleeve T, which turns by a screw-thread into a plate U, secured to the frame A, and at the other end the spring P' bears against a movable collar T', which has its 80 lower bearing against a collar V, fixed on the shaft B. By turning the sleeves R and T in the plates S and U, respectively, the tension of the springs P and P' may be adjusted as desired.

In use a quantity of ore mingled with refuse is thrown into the bowl E, and water is added thereto through the water-supply pipe F or by other convenient means. The discharge-pipe K' being uncoupled from the pipe K, the shaft and bowl are rotated rapidly, and the water and refuse material, which are lighter than the ore, are thrown off by the centrifugal motion of the bowl over its edge into the trough G, and is carried away through the 90 pipe I. The concave form of the bowl is adapted to permit and even to assist in the operation. The mass of ore and refuse in the bowl is kept from settling solidly in the bottom of the bowl while it revolves by the vertical movement produced through the step on the block N, whereby the water comes in contact with all parts of the mass of material, and by reason of the motion that the water 100

acquires from the rotation and shape of the bowl separates the lighter material from the ore and carries it over the edge of the bowl into the trough G, as heretofore described. 5 This operation may be carried on continuously until the refuse material has been thus separated from a considerable quantity of the ore, when the rotary motion is stopped, the plate M is removed, the gate L is opened, 10 and the ore is discharged through the pipe K, which may be led away by the pipe K', coupled to the pipe K, if desired.

What I claim as new, and desire to secure by Letters Patent, is—

- 15 1. In an ore-concentrator, the combination, with a rotating concentrator-bowl, of a short outwardly-projecting discharge pipe or nozzle fixed in the bottom of the bowl and provided with a water-tight gate located in the pipe at 20 a distance from the bowl, a removable plate-cover over the inner end of the discharge-pipe, and a removable hose adapted to be coupled to the discharge-pipe, substantially as described.
- 25 2. In an ore-concentrator, the combination, with a revoluble vertical shaft supporting thereon centrally a bowl adapted to hold a supply of ore and water, of a collar and block bearing against each other, one affixed to the

shaft and the other affixed to the frame, one 30 having a step and the other a recess for receiving the same, whereby by the revolution of the shaft it is given an endwise motion, and springs arranged about the shaft, having their bearings so located and arranged as to 35 limit and control the endwise movement of the shaft, substantially as described.

3. In an ore-concentrator, the combination of a concave ore-receptacle fixed upright on a centrally-piercing shaft, which shaft is provided with a collar bearing against a corresponding block on the frame, the block having a cam or step and the collar a corresponding recess, whereby as the shaft is rotated the receptacle is intermittently raised 45 and dropped, compression-springs coiled around the shaft having their bearings arranged to control the vertical motion of the shaft, and a circular trough located about the receptacle near its upper edge and arranged 50 to catch the overflow from the receptacle, substantially as described.

In testimony whereof I affix my signature in presence of two witnesses.

CHARLES E. SEYMOUR.
